(57) **CLAIM**

The ornamental design for a slatted table top, as shown and described.

DESCRIPTION

FIG. 1 is perspective view of the first embodiment of a slatted table top having a plurality of slots which extend all the way through the table top, showing my new design; FIG. 2 is a top plan view thereof;

FIG. 3 is a front elevational view thereof;

FIG. 4 is a right side elevational view thereof, the left side elevational view being identical;

FIG. 5 is a bottom plan view thereof,

FIG. 6 is a perspective view of a second embodiment of a table slat array having a plurality of slots which do not extend all the way through the table top, showing my new design;

FIG. 7 is a top view thereof;

FIG. 8 is a front elevational view thereof;

FIG. 9 is a right side elevational view thereof, the left side elevational view being identical; and,

FIG. 10 is a bottom plan view thereof.

The broken lines are for environmental purposes only and form no part of the claimed design.
